(57) **CLAIM**

We claim the ornamental design for a light emitting diode lamp unit, as shown and described.

DESCRIPTION

FIG. 1 is a top perspective view of a first embodiment of a light emitting diode lamp unit of the present invention;

FIG. 2 is a top view thereof;

FIG. 3 is a bottom view thereof;

FIG. 4 is a first side view thereof, wherein the second side view is a mirror image thereof;

FIG. 5 is a third side view thereof, wherein the fourth side view is a mirror image thereof;

FIG. 6 is a top perspective view of a second embodiment of a light emitting diode lamp unit of the present invention;

FIG. 7 is a top view thereof;

FIG. 8 is a bottom view thereof;

FIG. 9 is a first side view thereof, wherein the second side view is a mirror image thereof; and,

FIG. 10 is a third side view thereof, wherein the fourth side view is a mirror image thereof.
